TRAVELING BAG

Fred D. Stelljes, Newark, N. J., assignor to T. & L. Company Incorporated, Newark, N. J., a corporation of New Jersey

Application October 31, 1931. Serial No. 572,337

3 Claims. (Cl. 190—41)

This invention relates to traveling bags, and more particularly to improvements in traveling bags of the Gladstone type which have a partition dividing the bag into two compartments. 5 The usual Gladstone bag is divided into two compartments by a partition commonly formed of stiff cardboard covered with a fabric or of other stiff material. Heretofore, the partition has been held in place by means of tabs attached to the frame of the bag, the tabs and partition carrying co-operating snap fasteners. But such a manner of holding the partition in place is objectionable in that the frequent manipulation of the tabs bends the upper edge of the partition, causing it to become limp and sag, with the result that it is thereafter difficult to fasten the tabs to the partition by means of snap fasteners. Also, the bent and limp partition is unsightly and detracts from the appearance of the bag.

It is, therefore, an object of this invention to provide means for holding a partition in place in a Gladstone bag without resorting to snap fasteners or other means which tend to cause the partition to be limp and sag.

The two sections of a Gladstone bag are generally held together by fastening devices mounted on the frame members of the bag. The fastening device usually comprises pivotally mounted tongue members on one frame member, which tongue members pass through slots in the frame member, and thence through slots in members attached to the other frame member. When the bag is open, the slots in the frame member carrying tongues are unsightly and give the bag an unfinished appearance.

It is a further object of this invention to provide means to hold a partition in place when the bag is closed, and to cover the slots in the frame member when the bag is open.

These and other advantageous objects, which will later appear, are accomplished by the simple and practical construction and arrangement of parts hereinafter described and exhibited in the accompanying drawings, forming part hereof, and in which:

Figure 1 is a plan view of a Gladstone bag embodying my invention for holding a partition in place,

50 Figure 2 is a sectional view taken on line 3—3 of Fig. 6,

Figure 3 is a perspective view of my partition holding means, showing the manner in which it covers the slot in the frame member when the bag is open,

Figure 4 is another perspective view of the partition holding means in another position,

Figure 5 is a perspective view showing the manner in which the partition is held in place, the bag being closed with the bag fastening means in a raised position, and

Figure 6 is a similar perspective view showing the position of the parts when the bag is closed and the bag fastening means in a lowered position.

Referring to the drawings, in Fig. 1 is shown a Gladstone bag embodying my invention. The bag is provided with fastening devices for holding the frame members together. The fastening device includes plate 22, mounted on one frame member, and pivotally connected to plate 22 is a plate 20 having fixed thereto a tongue 21 which passes through a slot 31 in the top portion 18 of the frame member, (see Fig. 3).

Attached to the side portion 17 of the frame member by means of rivets 25 are plates 24, which are right angularly bent to prevent a section 23 resting against the underside of top portion 18 of the frame member, the section 23 having a slot registering with the slot 31 in the frame member. The plate 24 extends downwardly an appreciable distance below the lower edge of side portion 17 of the frame member to provide a surface upon which the upper edge 34 of the cut-out portion of partition 33 may rest, as shown in Fig. 5.

Pivottally connected at 26 to the plate 24 is a member 27, which is bent upwardly at 28, and then again bent to present a flat bar 29, having an upturned flange 30 (see Figs. 3, 4, 5) which covers the slot 31 when the bag is open, (see Fig. 3) and also having an upturned finger piece 32 by means of which the bar 29 may be conveniently moved.

When the bag is open, the bar 29 is moved to the position shown in Fig. 3 to cover the slot 31, and allow the partition 33 to be freely moved. When it is desired to close the bag, the partition is placed in position against the plate 24, and the bar 29 is moved to the position shown in Fig. 5 to hold the partition in place.

The other frame member 19 of the bag (see Fig. 2) has attached thereto a plate 36 having a slot 37 through which the tongue 21 passes to hold the frame members together in a well known manner. The plate 36 has a downturned flange 35 which rests upon the partition 33, when the bag is closed as shown in Figs. 5 and 6, the flange 35 being shaped so that it will not interfere with the bar 29. It will be readily seen that the par-

partition is securely held in place between the plate 24 and bar 29, and the flange 35, with no danger 5 of the partition being bent or otherwise damaged. Also, the inconvenience incident to the use of snap fasteners is eliminated; and when the bag is closed, the flange 35 insures the partition being pushed back to the frame member carrying the lock 40 and prevents the tongues 21 from cutting the binding of the partition as would be 10 the case should the partition not lie close to the plate 24.

Obviously, the plates 23, 24, 36 reinforce the frame members against sagging, and the flanges 35 cooperate with the bars 29, when in the position shown in Fig. 5, to center the frame members 15 so that the male members (not shown) of the lock 40 will readily enter the slots 41 of the lock 40.

From the above description it will be seen that I have provided a simple device for holding a 20 partition in place in a traveling bag without danger of bending or otherwise damaging the partition, the device serving also to cover slots in the frame member when the bag is open. Further, I have also provided means for reinforcing the 25 frame members and for insuring the position of the partition against the lock carrying frame member when the bag is closed to prevent the tongue of the bag fastening devices from cutting the edges of the partition.

The foregoing disclosure is to be regarded as descriptive and illustrative only, and not as restrictive or limitative of the invention, of which obviously an embodiment may be constructed including many modifications without departing 35 from the general scope herein indicated and denoted in the appended claims.

Having thus described my invention, what I claim as new and desire to secure by Letters Patent, is:

45

50

55

60

65

70

75

1. In a traveling bag of the Gladstone type having a pair of frame members, one of the frame members having slots therein, fastening means for holding the frame members together including tongues arranged to pass through said slots, a partition dividing the bag into two compartments, plates attached to the slotted frame member, said plates having slots registering with the slots in the frame member, and bars pivotally connected to said plates to hold the partition in a definite position when the bag is closed, said bars having flanges to cover said slots when the bag is open.

2. In a traveling bag having a pair of frame members, one of the frame members having slots therein, fastening means for holding the frame members together including tongues arranged to pass through said slots, a partition dividing the bag into two compartments, plates attached to the slotted frame member to provide a surface upon which the upper edge of the partition may rest, plates on the other frame member having slots through which the tongues also pass, and flanges on said last mentioned plates, said flanges forcing said partition against the first mentioned plates when the bag is closed to prevent the tongues from cutting the binding of the partition.

3. In a traveling bag having a pair of frame members, fastening means to hold the frame members together, a partition dividing the bag into two compartments, plates attached to one of the frame members to provide a surface upon which the partition may rest, and flanged members attached to the other frame member to force the partition against said plates and out of the way of the fastening means when the bag is closed.

FRED D. STELLJES.
